TABLE AND SEAT STRUCTURE

Joseph A. Paquette, San Mateo, Calif.

Application May 31, 1943, Serial No. 489,142

6 Claims. (Cl. 155—124)

My invention relates to a table with attached seats; and one of the objects of the invention is the provision of a combined structure in which the seats are accessible without the need for stepping over parts, and which is stable even though but one side is occupied. Another object is the provision of a structure of the character described which is both light in weight and amply strong; and which can be readily knocked down for shipment or storage in a compact package, and as readily set up for use.

My invention possesses other objects and features of value, some of which, with the foregoing, will be set forth in the following description of the invention. It is to be understood that I do not limit myself to the showing made by the said description and the drawing, as I may adopt variant forms of the invention within the scope of the appended claims.

In the drawing Figure 1 is a vertical sectional view of my table and seat structure, the plane of section being indicated by the line 1—1 of Figure 2. Figures 2 and 3 are respectively side and end elevations of the structure.

In terms of broad inclusion the table and seat structure of my invention comprises a table top with means for supporting it at the proper height of about 30 inches from the ground. A beam extending across, but below the top, is pendently supported from the top by suspender pieces; and a seat is arranged on each end of the beam in convenient position relative to the table top. The supporting means preferably comprise legs, the lower ends of which extend outwardly on each side far enough to lie in a vertical plane parallel to the edge of the table and passing through the seats on that side. Suitable struts for bracing the structure longitudinally and transversely are included. The parts are demountably connected for rapid knock-down and assembly; and where practicable, parts are so arranged that sub-assemblies of parts may be folded together to facilitate storage and handling.

In detail, my invention comprises a table top comprising the top panel 6 and the apron pieces 7 which form a stiff frame on all four sides and into which the panel is rabbeted. The top panel may be thin ply-board but preferably is ply-board provided with a hard, non-absorbent top sheet of compacted fiber. Cross pieces 8 extending between and secured to the long apron pieces also form part of the table top, tying it into a rigid, stable structure. They also provide additional support for the relatively thin top panel. For the table described there are six of

these cross pieces spaced as shown in Figure 2. For convenience in this description a table for serving meals to 12 persons will be considered. Such a table may be 30 inches wide and 12 feet long, and six seats are arranged on each long side.

Extending downward at the ends of the cross pieces and disposed on opposite sides thereon, are suspenders 9, each of which is fixed to the 10 apron by a bolt 11. A timber ring connector 12 is preferably interposed between the apron and suspender on the bolt 11 to add to the rigidity and strength of the connection.

Connecting the lower ends of each transverse 15 pair of the suspenders and extending outwardly beyond the edges of the table top on both sides is a beam 16. A rigid connection between beam and suspender is secured by a bolt 17 and timber ring connector 18; and it is to be noted that 20 the suspenders lie on opposite sides of the beam. On each end of the beam, a seat board 21 is fixed by bolts 22, and braced by corner blocks 23. The length of the suspenders and the proportion of parts is such preferably as to place 25 the seat about eighteen inches from the floor and at a convenient distance horizontally from the apron. Longitudinally extending struts 24, though not strictly necessary, are preferably arranged between the cross pieces 8 and the end 30 apron pieces, abutting against the top panel midway between its long sides. The central strut 24a above, and strut 26 below, extending between the central pair of beams 16, are bolted to the diagonal struts 27, disposed between the 35 center pair of beams and central pair of cross pieces. These members carry the stresses tending to wrack the structure lengthwise. Diagonal struts 28 are also bolted to cross pieces 8 and beams 16 to brace the structure crosswise. Preferably one is placed at each end and on the two middle beams. A long tie piece or strut 29 ties all the beams together.

Means are provided for supporting the table top from the floor. For the structure described 45 and shown, two pairs of legs 31 are sufficient. Each pair is disposed as an inverted V, adjacent the second beam from each end of the table. The vertex or upper ends of each pair are bolted to the adjacent cross piece 8, and the lower ends 50 are extended so that each lies vertically below the associated seat; that is, in a vertical plane parallel to the table edge and passing through the seats on that side. This arrangement makes a perfectly stable structure even though the six 55 seats on only one side are occupied, since the

center of gravity of the whole, including occupants of seats, is between the points of support.

It is convenient to arrange the legs of each pair to pass through the lower corners of the adjacent four-sided frame formed by cross piece, suspenders and beam; and in the frames involved I connect each leg to the frame corner by the bolt 17, passing through all three of the members, with timber ring connectors preferably disposed between the contiguous faces.

It is apparent from the above that an exceedingly light and strong table and seat structure results, the seats literally supported from the apron pieces forming part of the table top, which in turn is carried on the legs. This construction lends itself to the stacking and moving about which is required in mess halls where many men are fed. It will also be noted that each seat and its support leaves nothing to be stepped over, but is readily straddled without particular attention, which is important to one carrying a tray of food.

It will also be observed that because of the bolted construction, the parts may be readily demounted for storage or shipment and quickly reassembled by anyone without special skill or experience. One such knock-down procedure contemplates disassembly of the legs and braces; and the removal of bolts 11 to free the suspenders from the top structure. Then with the nuts back on the bolts 17, the suspenders may be turned down to lie along opposite sides of the beam to which they are connected, so that the total thickness of this subassembly of beam, two seats and two suspenders is only the depth of the beam plus the thickness of the seat board. Six such subassemblies together with braces, legs and hardware for one complete structure may be distributed over the underside of the table top subassembly; and the whole enclosed in a crate or case, the length and width of the table top, and a thickness or height less than twice the width of the apron pieces 7. These dimensions measure the space required for storage or a shipping case.

I claim:

1. A table and seat structure comprising a table top, legs supporting the table top, a plurality of spaced beams extending transversely of and below the table top, a seat arranged at each end of each beam, each seat being independent of the other seats and suspenders supporting the beams from the table top independently of the legs.

2. A table and seat structure comprising a table top, a plurality of spaced beams extending transversely of and below the table top, a seat arranged at each end of each beam, each seat being independent of the other seats, suspenders supporting the beams from the table top, and legs fixed to the table top and to certain of the beams and having their lower ends on each side of the table

in a vertical plane parallel to the edge of the table top and passing through the overlying seats carried by beams to which the legs are fixed.

3. A table and seat structure comprising a table top, a plurality of spaced beams extending transversely of and below the table top, a seat arranged at each end of each beam independently of the other seats, suspenders supporting each beam from the table top, and a plurality of pairs of legs fixed to the table top and having their lower ends on each side of the table in a vertical plane parallel to the edge of the table top and passing through the overlying seats, each of said legs being fixed to a selected suspender and beam at their juncture.

4. A table and seat structure comprising a table top, a plurality of spaced beams extending transversely of and below the table top, a seat arranged at each end of each beam, each seat being independent of the other seats, suspenders supporting the beams from the table top, legs fixed to the table top and to certain of the beams and having their lower ends on each side of the table in a vertical plane parallel to the edge of the table top and passing through the overlying seats, and strut means interposed between the legs bracing the top, suspenders and the beams interposed between the legs against wracking in all directions.

5. A table and seat structure comprising a table top, a plurality of spaced beams extending transversely of and below the table top, a seat arranged at each end of each beam, each seat being independent of the other seats, suspenders supporting the beams from the table top, legs fixed to the table top and to certain of the beams and having their lower ends on each side of the table in a vertical plane parallel to the edge of the table top and passing through the overlying seats, and strut means interposed between the legs longitudinally and transversely of the table top and bracing the top, suspenders and beams interposed between the legs against wracking.

6. A table and seat structure comprising a plurality of spaced substantially vertical four-sided frames having substantially horizontal upper and lower members, each lower member extending on both sides beyond the frame, a seat disposed on each outwardly extending portion of each lower member independently of the seats upon the outwardly extending portions of the other lower members, substantially horizontal apron pieces connecting the upper portions of the four-sided frames on opposite sides of the structure, a top panel disposed on the apron pieces and upper members, and a pair of legs fixed to each of a plurality of frames with their lower ends terminating under the associated seats.

JOSEPH A. PAQUETTE.
